(57) **CLAIM**

The ornamental design for an inflatable sleeping pad, as shown and described.

DESCRIPTION

FIG. 1 is a front, right, and top perspective view of an inflatable sleeping pad embodying the new design;

FIG. 2 is a rear, left, and bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right, and top perspective view of the inflatable sleeping pad in a condition of use; and,

FIG. 10 is a rear, left, and bottom perspective view thereof. The broken lines in FIGS. 1-8 are shown for the purpose of illustrating portions of the inflatable sleeping pad that form no part of the claimed design.
